UNITED STATES PATENT OFFICE.

HONOR DE SOUZA REMEDIOS, OF KOBE, JAPAN.

SANITARY-TOOTHBRUSH CONTAINER.

Application filed July 1, 1927. Serial No. 202,786.

The invention relates to means and method of maintaining a tooth brush in a sealed condition from the time it leaves the manufacturer to the time it is received by the ultimate user. Provision is also made for attaching a mailing tag to the said container containing the brush.

A principal object of the invention is to enclose a tooth brush, the bristle end of which has previously been completely wrapped and sealed, in a container having a hinged cover and provided with means for being sealed unitary with the tooth brush.

Another principal object of the invention is to provide means for attaching a mailing tag to the container.

Another principal object of the invention is to make the container of translucent or transparent material so that the condition of the tooth brush and seals can be examined without the removal thereof from the container and without disturbing the packing thereof.

Other objects will be apparent from this specification taken in connection with the accompanying drawings, in which:

Figure 1 is a side view of a container containing a sealed tooth brush therein embodying my invention;

Figure 2 is a similar view to Figure 1, the container being shown in longitudinal cross section, and the wrapper of the bristle end of the tooth brush within the container being torn partially away;

Figure 3 is a cross section of Figure 2 taken along the line 3-3 looking in the direction of the arrows;

Figure 4 is a detail view of the hinged cap or cover;

Figure 5 is a cross section taken along the line 5-5 of Figure 4 looking in the direction of the arrows; and

Figure 6 is a blank of a container before it has been folded.

Referring now in detail to the drawings, 7 represents a container of transparent material preferably made in rectangular form. One end of this container 8 is permanently closed, while the other end is provided with

a hinged cover or cap 9. Eyelet hinges 10 50 are preferably used on which the cover swings.

The cover 9 is provided with a perforation 11 and the container 7 is provided with a perforation 12, the said perforations being 55 adapted to co-operate with a tie 14 to secure the cover in closed position.

A tooth brush 15 the bristles end of which is wrapped in transparent material 16 secured by a seal 17, is inserted in the container, and the tie 14 is adapted to pass through a perforation in the handle of the tooth brush as shown in Figures 1 and 2. After this tie has been passed through the cover, handle of tooth brush, and container 65 as above described, the ends thereof are sealed by a double faced seal 18 between gummed surfaces of which the two ends of the tie are secured.

When the tooth brush and container have 70 been received by the ultimate user, he can upon examining the package, readily ascertain whether the tooth brush has been removed from the container or its packing disturbed, without removing the tooth brush 75 from the container or breaking the seals, due to the transparency of the container.

I have described what I believe to be the best embodiment of my invention. I do not wish to be confined in patent protection to 80 the embodiment shown but what I wish to cover by Letters Patent is set forth in the appended claims.

Claims:

1. In a sanitary tooth brush container, a 85 transparent box open at one end, a hinged cover at said open end, a tooth brush having a perforation in the handle thereof, said cover and box also having perforations therein, a tie adapted to pass through the 90 perforations of said box, tooth brush handle and cover, and a seal adapted to seal both ends of said tie.

2. In a sanitary tooth brush container, a tooth brush, securing means in the handle 95 thereof, a box open at one end, a hinged cover at said open end, perforations in said box and cover, and a tie adapted to pass

through said perforations of said box and cover and engage the securing means in the handle of said tooth brush, and a seal adapted to seal both ends of said tie.

5 3. In a sanitary tooth brush container, a tooth brush, securing means in the handle thereof, a box open at one end, a hinged

cover at said open end, perforations in said box and cover, and a tie adapted to pass through said perforations of said box and cover and engage the securing means in the handle of said tooth brush.

HONOR DE SOUZA REMEDIOS.
